(57) **CLAIM**

The ornamental design for a packing belt as shown and described.

DESCRIPTION

FIG. 1 is a front elevational view of a transparent embodiment of a packing belt showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a portion of the front elevational view of FIG. 1 enlarged for magnification purposes;

FIG. 10 is a portion of the perspective view of FIG. 7 enlarged for magnification purposes;

FIG. 11 is a front elevational view of an opaque embodiment of a packing belt showing my new design;

FIG. 12 is a rear elevational view thereof;

FIG. 13 is a left side view thereof;

FIG. 14 is a right side view thereof;

FIG. 15 is a top plan view thereof;

FIG. 16 is a bottom plan view thereof;

FIG. 17 is a perspective view thereof;

FIG. 18 is another perspective view thereof;

FIG. 19 is a portion of the front elevational view of FIG. 11 enlarged for magnification purposes; and,

FIG. 20 is a portion of the perspective view of FIG. 17 enlarged for magnification purposes.

In the drawings, the dash-dot-dash broken lines represent enlarged designations that form no part of the claim.

1 Claim, 20 Drawing Sheets
